UNITED STATES PATENT OFFICE.

CALVIN W. WELLMAN, OF OSHKOSH, WISCONSIN.

LOWERING DEVICE FOR CASKETS.

1,117,537.

Specification of Letters Patent. Patented Nov. 17, 1914.

Application filed January 16, 1914. Serial No. 812,423.

To all whom it may concern:

Be it known that I, CALVIN W. WELLMAN, a citizen of the United States, and a resident of Oshkosh, in the county of Winnebago and State of Wisconsin, have invented a certain new and useful Lowering Device for Caskets; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to burial apparatus. It particularly relates to apparatus for lowering caskets. In the construction embodying my invention, a means is provided for automatically regulating the rate of lowering movement irrespective of the weight of the load that is to be lowered.

I have provided a lowering device whereby caskets may be evenly and gently lowered, may easily and readily be modified in size to conform to the different sizes of caskets, which may be easily folded into a compact form and arrangement whereby it may be conveniently carried and which may also be easily unfolded and set for any requisite size.

The invention is applicable to a great variety of lowering devices and consequently constructions containing the invention may partake of a great variety of forms all of which come within the purview of my claims hereinafter appended. To show the practicability of constructions embodying my invention and the manner in which they may be operated, I have selected one of such constructions as an example and shall describe it hereinafter.

The construction selected is illustrated in the accompanying drawings, wherein—

Figure 1 illustrates a casket lowering device. Fig. 2 illustrates a transverse sectional view of one end of the casket lowering device. Fig. 3 illustrates a longitudinal section of the device. Fig. 4 illustrates a side view of one of the ends of the bars which support the load. Fig. 5 is a sectional view of the end telescoping parts. Fig. 6 is a sectional view of a modified automatic means for regulating the rate of downward movement of the load.

Referring to Fig. 1 of the drawings, 1 are

telescoping tubes forming the sides of the frames of the lowering device. The parts of the tubes engage with each other by a suitable means which prevent rotation of 60 part of the tubes with respect to other parts. They are rotatably supported in housings 2 located at their ends. The housings 2 also form standards for supporting the lowering device. The tubes 1 are connected together 65 by means of lowering straps 3. The ends of the lowering straps are secured to and wound upon the tubes 1. The ends of the tubes 1 are supported in the sleeves 10 located in the housings 2. The ends of the 70 tubes 1 fit over thimbles 12. The thimbles 12 are provided with pins 13 which set into notches 14 located in the ends of the tubes 1. The thimbles 12 are also provided with 75 spring pressed pins 15 which pass through thimbles and enter openings 16 located in the tubes 1. The pins 13 and 15 releasably lock the tubes 1 to the thimbles 12. The tubes 1 may be released from the thimbles 12 by merely pressing upon the pins 15 and 80 forcing them through the openings 16. The tubes around the openings 16 are provided with depressions 17 which enable the depression of the pins 15 to a point such that the edges of the openings 16 may engage 85 with the rounded tops of the pins 15 when the tubes 1 are pulled away from the thimbles 12. This will further depress the pins 15 and allow separation of the tubes 1 from the thimbles 12. The thimbles 12 are provided with slots 20 located in the bases or 90 ends of the thimbles. Blocks 21 are pivoted by means of the crosspins 22 in the end portions of the thimbles 12. They pass through the slots 20. The blocks 21 are also pivoted to the sleeves 10 by means of the pins 23 located in the ends of the blocks. The axes of the blocks 21 with respect to the hubs are at right angles to the axes of the thimbles 12. Universal joint connections 95 are thus formed between the tubes 1 and the sleeves 10 as well as between the tubes 1 and the supporting housings 2. The sleeves 10 are secured in the housings 2 by means of inwardly extending flanges 30 and 31 forming parts of the housings and the cap plates 32. The flanges 30 and 31 form also an outside bearing for the sleeves 10. The ends of the flanges 30 and 31 are located on the opposite sides of flanges 33 which are located centrally on the sleeves 10. The plates 32 are secured to the housings 2 by means of

the screws 34 located in the flanges of the caps and the rims of the housings. The sleeves 10, being secured to the tubes 1, when the frame has been connected together preparatory to the lowering of a casket, rotate with the tubes while the casket is being lowered.

A means is connected to the tubes 1 for automatically regulating the rate of movement of the casket while it is being lowered by the apparatus. The sleeves 10 at one end of the frame may be connected to a wheel 11 through the flanges 33 in which case the sleeves 10 will form the hubs of the wheels and the flanges 33 will form connecting webs between the hubs and the rims of the wheels. The peripherals of the wheels 11 may be provided with worm gears 40 which are adapted to operate on the worms 41 supported in sleeves 42 forming a part of the housings 2. The thread of the worms 41 and the teeth of the worm gears 11 have a 45 degree pitch so that when there is weight enough upon the straps, the wheels 11 will rotate, but inasmuch as the relative degree of angular movement between the wheels 11 and the worms 41 is so great, the worms 41 will allow the wheels to rotate substantially at the same rate irrespective to the load carried by the straps 3 and the loads placed on the straps will descend substantially at the same rate. The worms 41 are further controlled automatically to bring to substantial perfection the control of the rotation of the tubes 1 irrespective to the weight that they carry. The worms 41 are connected by their shafts 43 to friction brakes 53. Friction plates 44 are provided with leather washers or disks 45 which are located about the shafts 43 and are fitted snugly into the flanges or rims 46 located on the faces of the plates 44. The shafts 43 and worms 41 rotate in bearing sleeves 48 which are fixedly secured in the housing sleeves 42. The sleeves 46 are provided with plates 47 which coat with the plates 44 and disks 46 to form a brake on the movements of the shafts 43. The leather disks 45 are located intermediate between the plates 44 and 47. If desired, a spring 50 may be located in a socket 51 in one of the plates 44. The spring 50 presses on the center of the leather disk 46. This produces a slight frictional engagement between the disk 46 and the plate 47. When the wheels 11 are rotated toward each other by the weight of the load, they cause the rotation of the worms 41 and also they push the shafts 43 toward each other which causes more or less frictional engagement between the brake plates 47 and the leather disks 46. The contact between the plate 47 and the disk 46 at one corner of the frame will at first be central which will cause a light frictional engagement with the central part of the brake plate 47 when there is a light load.

on the straps 3; on the other hand, if there is a heavy load on the straps 3 the wheels 11 will force the shafts 43 toward each other with a greater pressure and cause a larger central portion of the disk 46 to be brought to bear upon the plate 47 and cause the plate 44 to press with greater pressure upon the disk 46 which will be forced with greater pressure against the brake plate 47. This will thus regulate the rate of rotation of the worm 43 and the rate of rotation of the wheel 11 and the descent of the load.

The plates 44 are secured to the shafts 43 by means of pins 52. The outer ends of the hubs of the plates 44 have substantially inner hyperboloidal shape which permit slight angular movement of the shafts 43 with respect to the plates 44, and prevent any binding between the plates 44 and the shafts 43 and produce a full contact on the disks.

In order that the lowering of the casket may be manually controlled, a manual means may be provided for releasing the brake and allowing the casket to descend at a greater rate than that which is permitted by the operation of the brakes. The ends 60 of the shaft 43 are enlarged and provided with end ball bearings 61. Sleeves 62 are located in the housing sleeves 42 and are adapted to move endwise to press against the ball bearings 61 which will in turn press against the enlarged ends 60 of the shafts 43. Levers 63 are fulcrumed on the top of the sleeve or telescoping parts 64 which fit over the housing sleeve 42. The levers 63 have forked ends 65 which are adapted to press against the sleeves 62 which cause endwise movement of the shafts 43 and relieve the pressure of the leather disks 46 on the plates 47 so that the shafts 43 may rotate more freely than is permitted by the operation of the brakes 53. The brakes are thus controlled by the operation of the levers 63.

The housings 2 are connected together at their ends by means of telescoping tubes 70 and 71. The width of the frame may be varied by merely pulling the telescoping tubes apart or pushing them together. Suitable means may be provided for securing the parts of the telescoping tubes in adjusted positions. I have provided pins 72 which are located in sockets 73. They are connected to knobs 74. The pins are spring actuated by means of the compression springs 75. The pins 72 pass through openings located in the central part 76 and 77 of the telescoping tubes 70 and 71. A plurality of openings 78 are formed in the sleeves or tubes 64 in which the pins 72 may be inserted. The parts of the tubes 70 and 71 may be pushed to any point so that the openings in the parts 76 and 77 register with the openings formed in the parts 64 through which the pins 72 may be inserted. The ends of the pins 72 are rounded which will per-

mit longitudinal movements of the parts 64 with respect to the parts 76 and 77 and when the openings register the pin will lock the parts together. The housings 2 may thus be placed at any desired distance apart and may be secured in their relative position by the pins 72.

The tubes 1 are also rotatively connected together. The enlarged ends 60 of the shafts 43 are provided with sockets 80. Tubes 81 are knuckled in the sockets 80 and are connected to the enlarged portion 60 of the shafts 43 by means of the pins 82. The inner walls of the sockets 80 are also hyperboloidal in shape to permit slight angular movements of the tubes 81 with respect to the shafts 43. The tubes 81 are provided with square openings 83 in which rods 84 having square cross sections slidably move. The diagonals through the cross sections of the rods are about the same as the diameter of the tubes, which prevent, to a great extent, angular movements of the rods with respect to the tubes. The rods 84 are connected together by means of the rotatable block 85 journaled in a sleeve 86 which are secured to the parts 76 of the telescoping tube 70. Longitudinal movements of the block 85 are prevented by washers and pins 89. The rods 84 are swiveled in sockets 88 located in the end of the cylindrical block 85 by means of pins 89. The rods 84 are provided with enlarged heads 90 which permit slight angular movements of the sleeves 85. The tubes 1 are thus connected together so that the rotation of one will also produce a rotation of the other. This will permit the maintenance of the casket in horizontal position while it is being lowered.

A means is provided for locking the parts and preventing rotation until control is given to the apparatus. A thumb screw 87 extends through the sleeve 86 and presses against a shoe 94 which frictionally engages the block 85.

The construction shown in Fig. 2 may be greatly varied. In Fig. 6 is shown one of the many modifications to which the construction shown in Fig. 2 is subject. The wheels 11 may be rotatably connected together through the tubes 81 and the rods 84 as in the form shown in Fig. 2. In the form shown in Fig. 6 the tubes 81 are connected to the shaft 95 in the same manner that the tubes 81 are connected to the shafts 43 in the form shown in Fig. 2. Each shaft 95 is journaled in the bearing sleeve 96 which is secured to the tube 64 forming a part of the telescoping tube 70. The sleeve 96 is secured in the housing 97 which forms one of the supports for the mechanism. The sleeve 95 is connected to a beveled gear 98. The wheel 11 is provided with a bevel gear 99 which meshes with the bevel gear 98. The rim of the wheel 11 is provided with the

worm gear 40. This operates on the worm 41 which forms part of the shaft 43.

Each shaft 43 is provided at one end with a brake 53 and at its other end with a manual means for releasing the shaft 43 from action of the brake 53. The lever 100 is pivoted to the tube or cap 101 which may be inserted over the housing sleeve 42. The lever 100 operates upon the bell crank lever 102, which is also fulcrumed on the cap 101. The lower end of the lever 102 is provided with a bearing point 103, which presses against the cylindrical block 104. The block 104 presses against the enlarged end 105 of the shaft 43. A ball bearing 106 may be interposed between the block 104 and the end 105 of the shaft 43. When the free end of the lever 100 is pressed it will operate upon the lever 102 to force the block 104 and the shaft 43 against the endwise pressure of the shaft 43 produced by the operation of the worm gear 40 and release the brake 53 which will permit a more rapid rotation of the shaft 43 and the tubes 1 which support the load.

The construction selected and described may be greatly varied in the arrangements and connections of its parts and in the substitution of elements having equivalent functions without departing from the spirit of the invention which is described in the claims in the language of the elements shown.

Having thus described my invention, what I claim as new, and desire to secure by Letters Patent, is,—

1. In a lowering device, a rotative part located on each side of the load, worm gears connected to the part, and a brake connected to the worm gears automatically operated by the weight of the load.

2. In a lowering device, a telescoping tube located on each side of the load and supporting the load, and worm gears connected to the said tubes, the worm gears rotatively connected together, and a brake operated by the weight of the load for controlling the rate of movement of the gears.

3. In a lowering device, a telescoping tube located on each side of the load, worm gear wheels secured to the telescoping tubes, worms operated by the worm wheels, brakes connected to the worms for automatically controlling the worms by the peripheral pressure of the wheels of the worms.

4. In a lowering device, a means located on each side of the load for supporting the load, a rotatable friction plate controlled by the movement of the said load, an automatic means for varying the area of frictional engagement of the said friction plate according to the weight of the load.

5. In a lowering device, a means located on each side of the load for supporting the load, friction plates controlled by the move-

- ment of the load, a coacting fixed friction plate, a leather disk interposed between the said plates and a means for varying the area of frictional engagement between the disk and the friction plate connected to the load.
6. In a lowering device, means located on each side of the load for supporting the load and a rotatable friction plate controlled by the movement of the load, a fixed coacting friction plate, a leather disk interposed between the said plates and secured at its periphery to the fixed plate, and a means for pressing the central portion of the disk toward the rotatable plate.
- 10 7. In a lowering device, a telescoping tube located on each side of the load for supporting the load, worm wheels connected to the tubes, worms operated upon by the worm wheels, brakes connected to the worms and operated by the peripheral pressure of the worm wheels on the worms, and telescoping parts for rotatively connecting the worms together.
- 15 8. In a lowering device, a telescoping tube located on each side of the load for supporting the load, worm wheels connected to the tubes, worms operated upon by the worm

wheels, brakes connected to the worms and operated by the peripheral pressure of the worm wheels on the worms, telescoping parts for rotatively connecting the worms together, and means for adjustably securing the parts of the tubes with respect to each other.

9. In a lowering device, a telescoping tube located on each side of the load for supporting the load, worm wheels connected to the tubes, worms operated upon by the worm wheels, brakes connected to the worms and operated by the peripheral pressure of the worm wheels on the worms, telescoping parts for rotatively connecting the worms together, means for adjustably securing the parts of the tubes with respect to each other, and a manual means for releasing the said brakes.

In testimony whereof, I have hereunto signed my name to this specification in the presence of two subscribing witnesses.

CALVIN W. WELLMAN.
